UNITED STATES PATENT OFFICE.

PATRICK F. CASSIDY, OF BOSTON, MASSACHUSETTS, ASSIGNOR, BY DIRECT AND MESNE ASSIGNMENTS, TO BOSTON BOTTLE WIRING AND LABELING COMPANY, OF SAME PLACE.

BOTTLE-LABELING MACHINE.

SPECIFICATION forming part of Letters Patent No. 678,833, dated July 16, 1901.

Application filed March 29, 1900. Renewed April 29, 1901. Serial No. 58,051. (No model.)

To all whom it may concern:

Be it known that I, PATRICK F. CASSIDY, a citizen of the United States, and a resident of Boston, in the county of Suffolk and State of Massachusetts, have invented certain new and useful Improvements in Bottle-Labeling Machines, of which the following is a specification.

This invention relates to machines for affixing labels to bottles.

The primary object is to provide improved means for insuring engagement of the paste-transferrer with the paste-roll on the downward stroke and prevent such engagement on the return.

A further object is to insure the separation of each label as it is affixed to a bottle from the remaining labels stacked in the hopper or on the label-bed; and further objects are to provide means for adjusting the hopper to accommodate labels of different sizes, to adjust the label-bed for various-sized bottles, and to construct a machine of this character which will be simple, strong, and durable.

The invention will be hereinafter fully set forth, and particularly pointed out in the claims.

In the accompanying drawings, Figure 1 is a side elevation of a label-attaching machine embodying my improvements. Fig. 2 is a vertical sectional view thereof. Fig. 3 is a front elevation, a portion of the standard being broken away. Fig. 4 is a plan view of the paste holder and transferrer. Fig. 5 is a horizontal sectional view on line 22, Fig. 1. Fig. 6 is a detail. Fig. 7 is a plan view of the label-bed. Fig. 8 shows in full lines the paste-roll in connection with the transferrer, the lowered positions of these two parts being indicated in dotted lines. Fig. 9 shows the position of the transferrer-rollers on the downward stroke—that is, as the transferrer is moving toward the labels. Fig. 10 shows the position of such rollers on the return of the transferrer. Fig. 11 shows the central section of the label-bed as depressed by a bottle.

Referring to the drawings, 1 designates a standard, and 2 a head mounted thereon having on its top a label-hopper. The bed 3 of this hopper is composed of two flat side plates

4 and a central flat plate 5, said plates having interlocking fingers 6, which permit the side plates to be moved laterally to accommodate between their opposite curved edges bottles of different sizes. These side plates, which are movable on the top of head 2, are normally held by pawls 7, engaging racks 8 on the front of the head. The central plate 5 is capable of being depressed by pressure on a bottle placed longitudinally thereon. It is mounted on a rod 9, encircled by a spring 10, which serves to hold a collar 11 of said rod against a boss 12, through which the rod is passed. Thus the central plate is held normally in line with the side plates. The labels rest centrally on plate 5 and are positioned thereon by side gages 13, supported on the upper ends of pivoted arms 14, which arms are connected by links 15 to opposite ends of a lever 16, fulcrumed on boss 12. A coil-spring 17, connected to the arms 14, tends to draw them together; but their positions may be readily regulated by a threaded rod 18, passed through a stud 19 and having a thumb-nut 20. Each gage is flanged at one end and is provided with an adjustable member 21, also flanged at one end and fitted with a screw passed through a slot and clamped by a nut 22. Each gage may be adjusted to accommodate labels of different sizes by moving its member 21 and the two gages may be relatively positioned by turning nut 20.

23 is a foot-treadle mounted in standard 1 and connected by a rod 24 to one arm of a bell-crank lever 25, fast on a shaft 26, supported by brackets 27, projecting rearwardly from head 2. The other arm of this bell-crank lever is projected into a cylinder 28 through a slot in the bottom thereof and connected to an arm of a piston 29. In the closed end of this cylinder is a screw 30, formed with longitudinal grooves to control the inlet and escape of the air. Adjustably mounted in an arm 31, projecting from the top of cylinder 28, is a gage 32, the front end of which acts as a stop to limit the insertion of a bottle across the label-bed.

33 33 are two arms fast on the end of shaft 26, said arms having weights 34 on their lower ends, which, together with coil-springs 35, 100

connected to said arms and to standard 1, tend to hold the arms in their normal nearly-upright position. The arms 33 at their upper ends support a paste-holder 36, to which 5 are also pivotally connected two guide-arms 37, which latter are pivoted at their lower rear ends to brackets 27. By this construction the paste-holder always maintains a horizontal position. Axially mounted within the 10 paste-holder is a grooved roll 38, the periphery of which extends through a slot in the top of the holder.

At the ends of the paste-holder are mounted two horizontally-disposed rails 39, upon 15 which travel rollers 40 of a paste-transferrer 41. This transferrer consists of a plate removably secured by a screw 42 to a cross-head 43, movable vertically at its ends on upright guide-rods 44, which latter are connected 20 at the top by a cross-bar 45 and supported at their lower ends by lateral projections of head 2. The paste-transferrer is formed on its under side with a series of grooved portions which are designed to engage with the 25 grooved paste-roll in the descent of the transferrer, but which are prevented from having such engagement as the latter moves upwardly. This is accomplished by mounting the axles of the rolls 40 in rearwardly-inclined 30 guideways 46. These consist of inclined plates 47, paralleling correspondingly-inclined lower edges of studs 48, depending from cross-head 43. As the treadle is depressed, causing the descent of the paste-holder across and 35 beneath the paste-transferrer, the rollers 40, which travel on rails 39, move to the forward ends of the inclined guideways, allowing the transferrer to engage with and effect the rotation of the paste-roll. As the paste-holder 40 ascends under the action of the spring-im- 40 pelled weighted arms 33 the rollers 40 move to the lower ends of the guideways, elevating the transferrer to such an extent relatively 45 to the paste-roll that as the latter passes rearwardly thereunder it is not engaged thereby. Hence at each operation the transferrer is brought into engagement with a fresh part 50 of the paste-roll.

49 49 designate two arms keyed on a shaft 50, supported by brackets 51, secured to the rear of head 2. On one end of this shaft is a crank-arm 53, carrying a small roller 54, which engages with a side piece on the adjacent arm 33. A coil-spring 55, secured at 55 one end to crank-arm 53 and at its lower end to one of the brackets 27, acts on shaft 50 to throw arms 49 downward across the labels when the paste-holder is lowered sufficiently to free the crank-arm 53 from engagement 60 with arm 33.

56 56 designate two rotary brushes axially mounted on crank-shafts 57, secured to the sides of head 2 by nuts 57^a in such manner that said shafts may be adjusted to position 65 the brushes closer together or farther apart. Each brush carries a pawl 58, engaging a ratchet 59, fast on shaft 57. This enables

the brushes to be turned in opposite directions to bring fresh surfaces into line for passage of bottles on which labels have been applied. 70

In practice a stack of labels is placed upon the bed of the hopper, the end gages are adjusted to hold the labels in position, and the plates 4 are laterally adjusted to accord with 75 the size of the bottles to which the labels are to be affixed. Thereupon the operator presses downwardly on the treadle, effecting the rocking of the carrying-arms 33 and the forward downward movement of the paste-holder, allowing the lowering of the paste-transferrer, the weight of which is upon the side rails 39. The transferrer having been supplied with paste by its engagement with the roll 38 bears upon the topmost label, which latter is prevented from adhering thereto by the arms 49. Pressure being released from the treadle, the paste-holder moves upward and backward, elevating the transferrer, but without contact of its roll therewith, the label-holding arms 80 49 being also raised out of engagement with the labels. Jarring or strain upon the parts as they return to their normal position is avoided by the piston 29, the escape of the air from cylinder 28 being retarded by screw 85 30. The operator then inserts the bottle lengthwise over plate 5 and against the stoppage 32 and bearing downwardly on said bottle depresses plate 5 and with it the labels, the topmost one of which will adhere to the 90 bottle. Thereupon pressure is relieved, and the bottle is moved downwardly between the brushes 56, which latter insure a smooth contact of the label with the bottle. In depressing plate 5 all of the labels thereon go with 95 it, and this bending of the labels causes the sides or ends of the lower labels to open back from the label adhering to the bottle and prevents more than one label being withdrawn at a time. 100

I claim as my invention—

1. A label-affixing machine comprising a paste-holder, a paste-transferrer, means for moving the former across the face of the latter as it approaches and also as it recedes 115 from the label-bed, said transferrer engaging said paste-holder as the former moves toward the label-bed, and means acting on one of said parts to prevent such engagement when the direction of the movement of the transferrer is reversed. 120

2. A label-affixing machine comprising a paste-holder, a paste-transferrer, the former being moved on a curved line and the latter on a straight line intersecting the line of 125 movement of the paste-holder, which latter is designed to engage with the paste-transferrer when the parts are moved in one direction only.

3. A label-affixing machine comprising a 130 paste-holder, a vertically-movable paste-transferrer carried by said paste-holder, means for moving the latter over and into engagement with the lower face of the paste-

- transferrer on the forward stroke, and means for preventing such engagement on the return stroke, as set forth.
4. A label-affixing machine comprising a paste-holder, a vertically-movable paste-transferrer carried by said paste-holder, means for moving the latter over and into engagement with the lower face of the paste-transferrer on the forward stroke, and means carried by the paste-transferrer for raising it relatively to the paste-holder on the return stroke, as set forth.
5. A label-affixing machine comprising a paste-holder having a projecting roll, a vertically-movable paste-transferrer carried by said paste-holder, means for moving the latter over the lower face of the paste-transferrer, said roll engaging said face, and means for raising the paste-transferrer relatively to the roll on the return stroke, as set forth.
6. A label-affixing machine comprising a paste-holder having a projecting roll, side rails carried by said holder, a vertically-movable paste-transferrer having rollers bearing on said rails, and means for moving the paste-holder over the lower face of the paste-transferrer, substantially as set forth.
7. A label-affixing machine comprising a paste-holder having a projecting roll, side rails carried by said holder, a vertically-movable paste-transferrer having rollers bearing on said rails, and inclined guideways for the axles of said rollers, and means for moving the paste-holder over the lower face of the paste-transferrer, substantially as set forth.
8. A label-affixing machine comprising a paste-holder, a roll mounted therein having a grooved periphery, a vertically-movable paste-transferrer carried by said paste-holder having a grooved face designed to engage with said roll on its downward movement, means for moving said paste-holder across said face of the transfferer and means for raising the transfferer relatively to the roll on the return stroke, substantially as set forth.
9. The combination with the shaft, and the arms carried thereby, of a paste-holder mounted between said arms and having a projecting roll, rails carried by said holder, means for operating said shaft, and a vertically-movable paste-transferrer having rollers bearing on said rails, the raising and lowering of said transfferer being effected by the movements of said paste-holder, substantially as set forth.
10. The combination with the shaft, and the arms carried thereby, of a paste-holder mounted between said arms and having a projecting roll, rails carried by said holder, means for operating said shaft, and a vertically-movable paste-transferrer having rollers bearing on said rails, and also having inclined guideways in which the rollers are free to move from end to end according to the direction of movement of the parts, substantially as set forth.
11. The combination with the shaft, the arms carried thereby, and means for holding said arms normally upright, of a paste-holder mounted between said arms, a vertically-movable paste-transferrer operated by the movements of said paste-holder, a treadle connected to said shaft, an air-piston and cylinder and a connection between said piston and said shaft, substantially as set forth.
12. The combination with the shaft, and the arms carried thereby weighted at their normally lower ends, of a paste-holder pivotally mounted between the upper ends of said arms, guide-arms also connected to the paste-holder, a vertically-movable paste-transferrer, upright rods therefor, said paste-transferrer being operated by the movements of said paste-holder, a bell-crank lever on said shaft, a treadle connected to one arm of said bell-crank lever, and a piston and its cylinder, one arm of said bell-crank lever being connected to said piston, substantially as set forth.
13. In a label-affixing machine, a bed or support for the labels composed of a central depressible member, and two stationary side members, the latter being arranged relatively to the former in such manner that labels resting on said depressible member will extend also onto said side members.
14. In a label-affixing machine, a bed or support for the labels composed of a central depressible member, two side members, and means for adjusting said side members laterally in relation to the central member to accommodate bottles of different sizes, substantially as set forth.
15. In a label-affixing machine, a label-bed having stationary side members and a central depressible member, all of said members having opposite interlocking fingers, substantially as set forth.
16. In a label-affixing machine, a label-bed having two laterally-adjustable side members formed with opposite fingers, and a central depressible member formed with side fingers interlocking with those of the side members, substantially as set forth.
17. In a label-affixing machine, a label-bed comprising two side plates, pawls carried by said plates, stationary rack-bars independent of said plates with which said pawls engage, said side plates having opposite fingers, and a central spring-held plate having fingers interlocking with those of the side plates, substantially as set forth.
18. In a label-affixing machine, a label-bed, side gages, arms carrying the latter, and means for relatively adjusting said arms, substantially as set forth.
19. In a label-affixing machine, a label-bed, side gages having adjustable sections, pivoted arms carrying said side gages, a lever, links connecting said arms to said lever, a spring between said arms, and an adjusting rod and nut for relatively adjusting said gages, substantially as set forth.
20. A label-affixing machine having a label-

bed, a paste-holder, arms carrying the latter, a paste-transferrer, a spring-impelled shaft having a crank-arm on one end designed to be engaged by one of said arms, and two arms 5 on said shaft designed to extend across said label-bed when the transerrer is lowered and to be raised therefrom when said crank-arm is engaged by the said carrying-arm.

21. In a label-affixing machine, two spaced-
10 apart circular brushes, two corresponding crank-shafts forming axles for and upon

which said brushes are rotatably mounted, and means adjustably holding said crank-shafts in place, whereby the axle portions of such shafts may be moved toward or away 15 from each other, substantially as set forth.

In testimony whereof I have affixed my signature in presence of two witnesses.

PATRICK F. CASSIDY.
